NAIL PULLER

Philip Brancati, Jackson Heights, N. Y.

Application February 11, 1939, Serial No. 255,994

1 Claim. (Cl. 254—23)

The present invention relates to new and useful improvements in nail pullers and has for one of its important objects to provide, in a manner as hereinafter set forth, a device of this character comprising a fulcrum of a novel construction and arrangement whereby nails may be expeditiously extracted substantially without bending thus permitting reuse thereof.

Another important object of the invention is to provide a tool of the character described which is adapted to be conveniently used as a hammer when desired.

Other objects of the invention are to provide a nail puller of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a nail puller constructed in accordance with the present invention, portions of the levers being broken away.

Figure 2 is a bottom plan view thereof.

Figure 3 is a top plan view.

Figure 4 is a cross sectional view, taken substantially on the line 4—4 of Fig. 1.

Figure 5 is a detail view in section through the hammer head, taken substantially on the line 5—5 of Fig. 1.

Figure 6 is a fragmentary view in side elevation, showing a portion of the jaws of the tool engaged with a nail to be pulled, a portion of a box being shown in vertical section.

Referring now to the drawings in detail, it will be seen that the embodiment of the invention which has been illustrated comprises a pair of levers 1 and 2 of any suitable metal. The forward end portions of the levers 1 and 2 are crossed and pivotally connected, as at 3. A recess 4 in the inner side of the lever 2 accommodates the adjacent portion of the lever 1.

Formed integrally with the forward end portions of the levers 1 and 2 are jaws 6 and 5, respectively. The forward end of the jaw 5 is formed to provide a claw 7. The jaw 6 terminates, at its forward end, in a prong or nose 8 which coacts with the claw 7. Formed integrally with the back of the jaw 6 is a hammer head 9.

Projecting from the lever 1, adjacent the pivotal connection 3, is an integral yoke 10. Journaled in the yoke 10 is a wheel or roller 11 which is engageable with a supporting surface adjacent the nail to be pulled. The yoke 10 and the

roller 11 constitutes a fulcrum which is designated generally by the reference numeral 12. It is thought that the manner in which the tool is used will be readily apparent from a consideration of the foregoing. In Fig. 6 of the drawings, the reference numeral 13 designates a portion of a box in which there is a nail 14 to be extracted. The jaws 5 and 6 are opened by swinging the levers 1 and 2 apart and the claw 7 is forced downwardly and up under the head 10 of the nail 14. The jaws 5 and 6 are then swung toward closed position in a manner to cause the head of the nail to be firmly gripped between the claw 7 and the prong or nose 8. With the fulcrum 12 resting on the box 13 the levers 1 and 2 are swung downwardly in a manner to lift the nail out of the box. During this operation the fulcrum 12, through the medium of the roller 11, travels on the box toward the nail in a manner to compensate for the arc described by the upwardly swinging jaws 5 and 6, thus permitting said nail to be pulled without being bent. It will therefore be seen that the nail may, if desired, be immediately reused without the necessity of straightening same. By simply turning the tool over it may be used as a hammer through the medium of the head 9. The intersecting portion of the lever 1 is also recessed, as at 15.

It is believed that the many advantages of a nail puller constructed in accordance with the present invention will be readily understood and although a preferred embodiment of the device is as illustrated and described, it is to be understood that changes in the details of construction may be resorted to which will fall within the scope of the invention as claimed.

What is claimed is:

A nail puller of the class described comprising a first handle member having an end portion extending at a slight angle therefrom, the inner portion of this end portion having a notch in one side therefrom and said portion terminating in a claw, the prongs of which extend upwardly and outwardly, a second handle member having an end portion extending upwardly and outwardly and then said portion extending downwardly at a slight angle and terminating in a prong for cooperating with the claw of the other handle member, that portion of the end part which extends upwardly and outwardly having a notch in its inner face which cooperates with the notch of the other handle member, a pivot passing through the notched parts for pivotally connecting the two handle members together, a yoke extending downwardly from the second handle member at the point where the upwardly and outwardly extending end portion joins with the major portion of said handle member and a roller carried by the yoke.

PHILIP BRANCATI.
